BRASSIÈRE OR SIMILAR GARMENT

Harry Gluckin, New York, N. Y., assignor to The
Gluckin Corporation, New York, N. Y., a cor-
poration of New York

Application February 10, 1945, Serial No. 577,170

8 Claims. (Cl. 2-42)

1

This invention relates to garments employing breast pockets or cups, with means for supporting the same upon the body of a wearer and at times constructed as brassières. More particularly, the invention relates to garments of the kind described employing brace or supporting members in the form of straps or bands which, in certain adaptations of the invention, extend continuously from upper inner side portions of the cups or pockets and are yieldably or otherwise attached to outer side edges of the same pockets, the straps or bands of opposed pockets being coupled together centrally of the brassière in link, plate or strap portions which may or may not have extensible or elastic properties. Still more particularly, the invention deals with brace or supporting straps or bands including stiffening or reinforcing members for firmly supporting the breasts of a wearer in raised youthful position. The novel features of the invention will be best understood from the following description when taken together with the accompanying drawing in which certain embodiments of the invention are disclosed, and in which the separate parts are designated by suitable reference characters in each of the views, and in which:

Fig. 1 is a perspective front view of a brassière made according to my invention, showing one adaptation thereof.

Fig. 2 is an enlarged sectional view on the line 2-2 of Fig. 1, showing only the strap member or band; and

Fig. 3 is a front view of the central portion of a brassière showing a modified form of coupling between the strap members.

In illustrating one adaptation of my invention, I have shown in Fig. 1 of the drawing two substantially similar pockets 10 and 10a, and as these pockets are of identical construction, the brief description of one will apply to both. My invention is not particularly concerned with just how each pocket proper is constructed. However, in the structure as shown, each pocket comprises an upper portion 11 and a lower portion 12 joined together along the curved seam, as at 13, which is designed to give the bust conforming contour to each pocket. Attached to side edges of the pockets 10 and 10a are side and back bands 14 and 15 having suitable means for detachably coupling the same at the center of the back, at the section indicated at 16. The rear portions of the bands 14 and 15 also preferably include elastic inserts 17 and 18 to yieldably support the brassière upon the body of the wearer.

The lower portions 12 of the pockets 10 and 10a

55

metal, bone, plastic or similar materials can be re-

2

are joined centrally of the front of the garment by a band 19 which may be elastic to further provide yieldable support of the garment and to provide relative movement of the pockets one with respect to the other. Shoulder straps 20 and 21 are coupled with the bands 14 and 15 respectively and to the upper contracted ends 22 of the pockets 10 and 10a, the coupling being made through the medium of straps 23 and buckles 24, providing adjustment of the straps 20 and 21.

Extending integrally from inner edge portions 25 of the upper parts 11 of the pockets 10 and 10a are brace or supporting strap members 26. These strap members pass through apertures 27 in a coupling, link, plate or strap 28 and are folded backwardly to extend over lower portions 12 of associated pockets 10 and 10a with the ends of the straps coupled to outer side edges of the pockets, preferably through the medium of elastic straps 29. In other words, the brace or supporting strap which extends integrally from the edge 25 of the pocket 10 extends over the lower portion 12 of this pocket and the same is true of the pocket 10a. A longitudinal section is shown through one of the straps 26 in Fig. 2 of the drawing on an enlarged scale. It will first be understood that at least the upper portions 11 of each pocket 10 and 10a is composed of two facing sheets, particularly at the edge portions 25 thereof.

In Fig. 2, the reference numeral 30 represents what would constitute the inner facing of the pocket by reason of the fold in the strap 26 and the reference numeral 31, the outer face of the pocket. It will thus be seen that the facing 30 becomes the outer facing of the strap 26, as appearing in Fig. 1, and the facing 31 the inner facing of the strap. The facing 31 of the strap has a transverse slit or cut, preferably reinforced as a buttonhole or opening 32, which facilitates insertion of a reinforcing or stiffening member or strip 33 into position between the facings 30 and 31. It is also preferred that a closure flap 34 be attached to the facing 30, by transverse stitching 35 to allow the flap to extend through the buttonhole or opening 32 beneath the facing 30 to retain the member or strip 33 against accidental displacement from the chamber which is formed between the facings 30 and 31 of the strap 26. It will be understood that by pulling out on the flap 34, the buttonhole will become open for the removal of the member or strip 33, and also to facilitate insertion of the member. By this construction, relatively stiff or rigid members of

moved in the laundering of the garment. The use of the term rigid or stiff is in comparison with flexible cloth or fabric, it being understood that the members are flexible to the degree to bend in conforming with the contour of the breasts. In some instances, paddings may be used as the reinforcing or bracing elements or straps, and these need not necessarily have the stiff or rigid characteristics mentioned above, nor is it at all times necessary that the strips or elements be removable.

The link, plate or strap 28 is preferably, but not necessarily composed of a relatively stiff and rigid material such as plastics in order to provide sliding movement of the straps 26 through the openings 27 thereof. These members actually operate to balance the support of the straps 26, and to take up the bust support through the inner edge portions 25 and the shoulder straps. By extending the straps backwardly upon respective pockets in the manner defined, a more concentrated support is provided for the breasts arranged in each pocket directly to outer side edges of the pockets, preferably at the lower portions thereof, which support is in turn taken up by the side and back bands 14 and 15. In some instances, the straps 23 may be composed of elastic materials.

In Fig. 3 of the drawing I have shown a slight modification of the construction illustrated in Figs. 1 and 2, the sole difference being in constructing the coupling, link, plate or strap of two parts rather than the one part 28, as shown in Fig. 1. In Fig. 3, two coupling parts in the form of links, plates or straps 36 and 37 are employed. These straps have outer elongated apertures 38 and 39 which are similar to the apertures 28 and through which supporting straps 40, similar to the straps 26 are adapted to pass.

The couplings 36 and 37 also have at adjacent edges apertures 41 and 42 through which an elastic or other strap 43 passes, in order to provide flexible connections between the members 36 and 37 and relative movement when the straps 43 are composed of elastic material. In Fig. 3, inner portions of two similar pockets are shown at 44 and 44a, which are equivalent to the pockets 10 and 10a. The lower portions 45 of the pockets are joined centrally by a strap 46, similar to the strap 19, the upper portions of the pockets are partially shown at 47 united to the lower portions 45 by the seams 48. The straps 40 are continuous with the inner edge portions 49 of the upper parts 47 of the pockets, in other words, are similar to the inner edge portions 25.

As the straps 40 are identical with the straps 26, no further detail description will be given with regard to the wall structure thereof. For purposes of identification only, 50 will represent the buttonhole similar to the buttonhole 32, 51 the closure flaps similar to the flaps 34, and 52 the strips or elements similar to the elements 33.

By providing the coupling, comprising the two parts or members 36 and 37, greater flexibility will be provided in the coupling between opposed straps 40, and when an elastic is employed, a greater yieldability of the straps 40, as well as inner edge portions 49 will be provided in adapting the breast pockets as well as the bracing straps to proper support of the breasts of a wearer.

In considering Fig. 1 of the drawing, it will be apparent that the breasts will be supported between the peripheral edges of the upper parts of the pockets as well as the lower portions thereof

reinforced by the brace straps, producing what might be termed breast enveloping bands which are flexibly and otherwise joined at the front of the garment by the strap coupling 28, and its equivalent shown in Fig. 3, and the band 19—46, supported further by the side and back bands which are coupled together at the back of the garment and the shoulder straps employed.

In most instances, supporting straps of the kind under consideration have been arranged to extend from one pocket to the other or opposed pocket, usually crossed centrally of the garment. With my present construction, the supporting and bracing straps are concentrated to the environment of each pocket and the breasts supported therein, thus producing more efficient results in the support of the breasts in raised youthful position and in controlling spaced relationship of the breasts one with respect to the other. In this connection, the spacing between the loops or apertures 27 as well as 38 and 39 can be controlled by the size of the coupling, link, plate or strap employed.

It will, of course be understood that the straps 26—46 need not be formed as integral parts of the facings employed in constructing the upper parts of the pockets. However, it is preferred that these straps extend from the inner edge portions 25—49 and thus can be well regarded as continuous or extensions of said edge portions.

Having fully described my invention, what I claim as new and desire to secure by Letters Patent is:

1. In garments of the class described, a pair of similar breast pockets, each pocket having a brace member extending continuously and freely from the upper inner edge portion of the pocket to the outer side edge of said pocket, means coupling adjacent inner edge portions of the members of both pockets at adjacent inner ends of the pockets, said means comprising a plate having spaced apertures through which said members pass in providing relative movement between the members of opposed pockets, said members having yieldable couplings connected to the outer side edges of the pockets, and stiffening elements arranged throughout the major portion of the length of said members.

2. In garments of the class described, a pair of similar breast pockets, each pocket having a brace member extending continuously and freely from the upper inner edge portion of the pocket to the outer side edge of said pocket, means coupling adjacent inner edge portions of the members of both pockets at adjacent inner ends of the pockets, said means comprising a plate having spaced apertures through which said members pass in providing relative movement between the members of opposed pockets, said members having yieldable couplings connected to the outer side edges of the pockets, stiffening elements arranged throughout the major portion of the length of said members, and means comprising openings in said members for detachably coupling the elements with respect to said members.

3. In garments of the class described, a pair of similar breast pockets, each pocket having a brace member extending continuously and freely from the upper inner edge portion of the pocket to the outer side edge of said pocket, means coupling adjacent inner edge portions of the members of both pockets at adjacent inner ends of the pockets, the member of each pocket having a chamber extending throughout the major por-

tion of the length thereof, a stiffening element arranged in said chamber.

4. In garments of the class described, a pair of similar breast pockets, each pocket having a brace member extending continuously and freely from the upper inner edge portion of the pocket to the outer side edge of said pocket, means coupling adjacent inner edge portions of the members of both pockets at adjacent inner ends of the pockets, the member of each pocket having a chamber extending throughout the major portion of the length thereof, a stiffening element arranged in said chamber and said members at one end portion of the chambers having openings for detachably coupling the elements with said members.

5. In garments of the class described, a pair of similar breast pockets, each pocket having a brace member extending continuously and freely from the upper inner edge portion of the pocket to the outer side edge of said pocket, means coupling adjacent inner edge portions of the members of both pockets at adjacent inner ends of the pockets, the member of each pocket having a chamber extending throughout the major portion of the length thereof, a stiffening element arranged in said chamber said members at one end portion of the chambers having openings for detachably coupling the elements with said members, and means retaining the detachable elements against accidental displacement from said members.

6. The combination with garments having breast pockets, with means supporting the pockets upon the body of a wearer, of brace members for said pockets, said members comprising extensions of inner upper edge portions of the pockets folded backwardly upon and extending freely over lower portions of respective pockets, ends of said members being attached to outer sides of the pockets, and means engaging the folds of said members intermediate the pockets for coupling members and pockets together.

7. The combination with garments having breast pockets, with means supporting the pockets upon the body of a wearer, of brace members for said pockets, said members comprising ex-

tensions of inner upper edge portions of the pockets folded backwardly upon and extending freely over lower portions of respective pockets, ends of said members being attached to outer sides of the pockets, means engaging the folds of said members intermediate the pockets for coupling said members and pockets together, and said last named means comprising apertured plates and yieldable coupling joining said plates in providing relative movement between folded portions of said members.

8. The combination with garments having breast pockets, with means supporting the pockets upon the body of a wearer, of brace members for said pockets, said members comprising extensions of inner upper edge portions of the pockets folded backwardly upon and extending freely over lower portions of respective pockets, ends of said members being attached to outer sides of the pockets, means engaging the folds of said members intermediate the pockets for coupling said members and pockets together, said last named means comprising apertured plates and a yieldable coupling joining said plates in providing relative movement between folded portions of said members, and said members having reinforcing elements extending throughout the major portion of the length thereof.
